UNITED STATES PATENT OFFICE.

ERNEST GONZENBACH, OF MILWAUKEE, WISCONSIN.

AUTOMATIC STOP-VALVE.

SPECIFICATION forming part of Letters Patent No. 756,845, dated April 12, 1904.

Application filed April 15, 1903. Serial No. 152,655. (No model.)

To all whom it may concern:

Be it known that I, ERNEST GONZENBACH, a citizen of the United States, residing at Milwaukee, in the county of Milwaukee and State 5 of Wisconsin, have invented a new and useful Automatic Stop-Valve, of which the following is a specification.

This invention relates to automatic stop-valves for use in connection with pneumatic 10 controlling systems for railroad and street-car trains.

The object of the invention is to provide means which are simple and efficient whereby as a train separates or parts through accident or otherwise the air-chambers which are 15 open to a supply of air under pressure, are automatically closed to prevent the exhaust of the air-pressure therefrom and at the same time such air-chambers are opened automatically 20 to the brake-cylinders.

Other objects of the invention will appear more fully hereinafter.

The invention consists, substantially, in the construction, combination, location, and relative arrangement of parts, all as will be more 25 fully hereinafter set forth, as shown in the accompanying drawings, and finally pointed out in the appended claims.

Referring to the accompanying drawings 30 and to the various views and reference-signs appearing thereon, Figure 1 is a view in plan, somewhat diagrammatic, illustrating the hose connection between the proximate ends of adjacent cars and embodying the principles of my 35 invention. Fig. 2 is a broken detail view in section on the line 2 2 of Fig. 1 looking in the direction of the arrows. Fig. 3 is a detail view in section on the line 3 3 of Fig. 2 looking in the direction of the arrows. Fig. 40 4 is a view in section on the line 4 4 of Fig. 2 looking in the direction of the arrows. Fig. 5 is a detail view in section on the line 5 5 of Fig. 4 looking in the direction of the arrows.

The same part is designated by the same 45 reference-sign wherever it occurs throughout the several views.

In the operation of trains of cars equipped with straight air-pressure systems for controlling the motors operating the brakes and 50 the like it is important to provide means

whereby should the train break in two the exhaust of the air-pressure from the pipe system by reason of such break is automatically prevented. It is also important to provide means whereby upon the breaking in two of 55 a train the brakes may be automatically applied. It is among the special objects and purposes of my invention to provide means for accomplishing these and other results.

Ordinarily the piping system with which 60 each car is equipped for carrying and handling the air-pressure is connected through suitable hose-sections to the piping system of the next adjacent car in the train, and in carrying out my invention I propose to provide 65 means operated by the pull on these coupled hose-sections between the ends of the cars for automatically operating suitable valves to close the piping system on each car to exhaust through the break in case the train 70 should break between the cars and at the same time to open the piping system on each car to a brake or other cylinder.

Referring to the accompanying drawings, 75 reference-signs A B designate the hose-sections between the ends of adjacent cars, adapted to be coupled together, so as to connect the piping system on one car with that on the next adjacent car to complete the piping system throughout the train. Any suitable form 80 of hose connection for coupling these sections may be employed. I have therefore merely indicated a conventional coupling and do not desire to be limited in respect to the character of the coupling employed. I have shown 85 two sets of hose-sections A B for coupling up two sets of pipes on the adjacent cars, but do not desire to be limited in this respect, and I will describe only one set or system, it being understood that the same description will apply 90 to the other system and connections shown.

Mounted upon the proximate end of each car is an air-chamber C, the hose-section A communicating with the casing C on the end of one car and the hose-section B communicating 95 with the corresponding chamber or casing C on the proximate end of the next adjacent car. The casing C contains an interior chamber D, with which communicates, through a nipple or other suitable connection, (indi- 100

cated at E,) a pipe F, adapted to deliver there-
to or therefrom the air under pressure from
any suitable or convenient reservoir or source.
The casing C is provided with a central cylin-
5 dical hub part G, formed with openings or
passages H therethrough. Sleeved upon the
central hub part G is a cylindrical flange J of
a part L, arranged to be received in a journal-
bearing in the front plate K of the air-cham-
10 ber casing. This cylindrical flange J is pro-
vided with lateral openings or passages M
therethrough, which when said cylindrical
flange J is rotated covers or uncovers the
openings H in the central hub-flange G of the
15 air-chamber casing. The cylindrical flange J
is formed with or is connected to a radial cir-
cular flange N, through which is formed an
opening O, arranged to coöperate with a nipp-
le or other plug connection or opening P,
20 with which communicates a by-pass Q. Thus
the part L, with its connected or associated
flanges J and N coöperating with the open-
ings H and P, constitutes a valve for con-
trolling such openings, whereby when said
25 part L is rotated the openings H and M may
be brought into register, as indicated in Fig.
3, to open communication between the inter-
ior of the air-chamber D and the part L, to
the latter of which may be connected in any
30 suitable manner a pipe or other connection R
for connection with the hose-sections A B, or
said openings may be brought out of register,
as indicated in Fig. 5, by rotating said part
L in the opposite direction, thereby cutting
35 off communication between the interior of
chamber D and the nipple or part L and pipe
R and hose-sections A B, such movement at
the same time bringing the opening O into
register with the opening P to open up com-
40 munication between the interior of chamber
D and the by-pass pipe Q. This by-pass pipe
Q may communicate with a brake or other
cylinder—as indicated, for instance, in dotted
lines at S—to apply the brakes, or such by-
45 pass may lead to any other apparatus, as may
be desired—such, for instance, as means for
arresting the motor.

The hose-sections A B are connected to the
50 parts L through elbows T, so arranged that
when the breaking strain such as would part
the train between the cars is imposed upon
the hose-sections the elbows T, and with them
the parts L, are rotated, thus operating the
55 valves and controlling the openings in the
manner above described, thereby cutting off
the air-chambers D from the source of supply
or to exhaust and at the same time opening
up the communication through the by-pass Q
to the brake or other cylinder S. Under nor-
60 mal conditions when the hose connections are
coupled up the elbows T are held in such po-
sition that the port-openings H M are in reg-
istering relation with respect to each other
and the opening P is closed; but when the
65 train parts and the elbows are rocked the port-

openings H M are closed, thereby cutting off
exhaust of the air-pressure to the outer air
through the broken hose connection, and the
same movement opens or brings into register
the openings O P to the by-pass, thereby
70 opening communication between the air-cham-
ber D and such by-pass and thence to the
brake or other cylinder supplied therethrough.

Many variations and changes in the details
of constructions and arrangement would read-
ily occur to persons skilled in the art and still
fall within the spirit and scope of my invention.
I do not desire, therefore, to be lim-
ited or restricted to the exact details shown
and described; but,

Having now set forth the object and nature
of my invention and a construction embody-
ing the principles thereof, what I claim as new
and useful and of my own invention, and de-
sire to secure by Letters Patent, is—

1. An automatic stop-valve for pneumatic
pressure systems for railroad-trains, comprising
an air-chamber, a valve arranged therein,
a connecting-hose and means operated by the
breaking strain of the hose when the train
90 parts for automatically operating said valve
and causing different ports to open and close
respectively, as and for the purpose set forth.

2. In an apparatus of the class described, an
air-chamber, a valve arranged therein and op-
erating to open and close said chamber to the
source of pressure, and a hose-section con-
nected to said valve, whereby a pull upon said
section moves said valve to close the ports
controlled thereby, as and for the purpose set
100 forth.

3. In an apparatus of the class described, a
piping system mounted upon adjacent cars of
a train, hose-sections for connecting said piping
systems together, a valve arranged to con-
trol the communication between said hose-
sections and said piping systems, and means
whereby said valves are operated to close said
communication by the strain imposed upon
said sections by the breaking of the train, as
105 and for the purpose set forth.

4. In an apparatus of the class described, a
piping system mounted upon adjacent cars of a
train, hose-sections for connecting said piping
systems together, a valve arranged to control
the communication between said hose-sections
and said piping systems, means whereby said
valves are operated to close said communica-
tion by the strain imposed upon said sections
by the breaking of the train, and means for
simultaneously opening communication be-
tween said piping systems and a brake-cylin-
der, as and for the purpose set forth.

5. In an apparatus of the class described, a
piping system adapted to be mounted upon
two or more cars of a train, and including an
air-chamber on each car, hose-sections for
coupling the chambers upon proximate ends
of adjacent cars, a valve arranged to control
the communication of said chambers with said

sections, and means whereby the strain exerted upon said sections by the parting of the train between said cars operates said valve to close said communications, as and for the purpose set forth.

6. In an apparatus of the class described, a piping system adapted to be mounted upon two or more cars of a train, and each including an air-chamber, hose connections between the air-chambers upon the proximate ends of adjacent cars, a brake-cylinder, a by-pass communicating between each of said cylinders and chambers, valves arranged within said chambers, and means operated by the strain imposed upon said hose-sections by the parting of the train for operating said valves to close communication between said cylinder and hose-sections and to open communication through said by-pass, as and for the purpose set forth.

7. In an apparatus of the class described, the combination with a piping system upon each of two or more cars of a train, and a brake-cylinder, means for opening communication between said piping system and said brake-cylinder, and means for opening communication between the piping systems on adjacent cars, including hose-sections, and means actuated by the strain upon said hose-sections upon the breaking of the train between said cars for opening communication between the piping systems and brake-cylinders.

ders on each car, and means also operated by the strain imposed upon the hose-sections upon the breaking of the train between said cars for closing the communication between said piping systems and said hose-sections, as and for the purpose set forth.

8. In an apparatus of the class described, a valve box or casing having a central cylindrical sleeve forming a hub, ports in said sleeve or hub, and additional ports on one radial face of the box or casing, a valve having a radial flange, and ports coöperating with the ports of the valve-box, and a hose-section connected to said valve and arranged to operate the same, as and for the purpose set forth.

9. The combination with an air-chamber adapted to communicate with a source of pressure, a brake-cylinder, a by-pass arranged to open communication between said chamber and cylinder, a hose-section, a revolute valve arranged within said casing for controlling said by-pass and said hose-section, and an elbow respectively connected to said valve and hose-section, as and for the purpose set forth.

In witness whereof I have hereunto set my hand, this 13th day of April, 1903, in the presence of the subscribing witnesses.

ERNEST GONZENBACH.
